CROSSING GATE

Joseph H. Staley, Columbus, Ind.

Application November 29, 1932, Serial No. 644,839

3 Claims. (Cl. 39—7)

This invention relates to the art of traffic crossing gates and particularly to a type of gate which may swing downwardly to a horizontal position to guard a crossing and which will be then normally maintained across a lane of traffic but which may be yieldingly swung horizontally to prevent breakage of the gate should a vehicle strike the lowered gate. Reference is made to Patent No. 1,985,958 granted to me on January 1, 1935.

In this type of gate considerable difficulty has been had in providing an actuating mechanism which could be mounted within the gate standard and connected with the gate itself without a complicated mechanism being required. A primary object of my invention is to provide a structure easily manufactured and assembled and which will be reliable under all operating conditions. Another object of the invention is to provide means preventing the raising of the gate while the gate is in some such position other than across the lane of traffic whereby the gate could not be raised to interfere with wires or other elements which may be present at the side and above the gate.

A further object of the invention is to provide means for holding the lowered gate in its normal position across the lane of traffic and permit it to be swung therefrom only upon the application of a force exceeding that normally returning the gate.

These and other objects and advantages will become apparent in the following description of the invention and reference is made to the accompanying drawings in which

Fig. 1 is a fragmentary central vertical elevation through a structure embodying my invention;

Fig. 2, a horizontal transverse section on the line 2—2 in Fig. 1;

Fig. 3, a central vertical elevation at right angles to that shown in Fig. 1;

Fig. 4, a fragmentary top plan view of the structure;

Fig. 5, a central vertical section through the operating cylinder;

Fig. 6, a detail in vertical section of the head latching means;

Fig. 7, a side elevation of the motor switch on a slightly enlarged scale;

Fig. 8, a side elevation of the control mechanism as viewed from the side opposite to Fig. 1;

Fig. 9, a wiring diagram, and

Fig. 10, a side elevation of a pair of gates shown in a lowered position guarding a crossing.

Like characters of reference indicate like parts throughout the several views.

I form a standard to have a base 10, a main housing 11, a head mounting ring 12, a head 13, and a head cap 14. The housing 11 is a hollow body, the principal portion of which is cylindrical with a rectangular section extending therefrom having an opening on its outer side. This opening is provided with a flange therearound to carry a packing or gasket 15 against which a door 16 is pressed by inserting its upper edge to under a depending flange 17 and swinging the lower end around against the gasket and securing it in place by a cap screw 18 passed through the door into the flange at the lower side. This door 16 is provided with openings 19 and 20 toward the top and bottom respectively over which hoods project and behind which are mounted screens so that a circulation of air may be had between the inside and outside of the housing without the entrance therewithin of foreign matter.

The head mounting ring 12 is a cylindrical section having the same outside diameter of that of the cylindrical portion of the body or housing 11 and is made in a separate piece solely to facilitate machining of its upper end so as to receive thereon a plurality of ball bearings 21 spaced therearound in an annular groove. The mounting ring 12 is secured to the housing 11 by telescoping it over an upturned flange and passing cap screws through ears turning inwardly respectively from the two members.

The ring 12 is provided with an arm 22 extending from one side thereof to the center, the outer end of the arm being bored through vertically and centrally of the ring to slidably receive a pin 23 therethrough. This arm 22 is provided with an opening near the wall of the ring 12 into which is inserted a pulley wheel 24 and a pin 25 is entered through a bore provided in the ring 12 from the outside to pass revolvably through the wheel 24 so as to provide an axle therefor on which the wheel may turn. The pin 25 is securely held in place by means of a set screw passed through the arm to bear against the pin from the inside of the ring 12.

The head 13 is a cylindrical member having its under side formed with an annular groove to receive the upper sides of the balls 21 therein and is further formed to have a downturned flange 26 extend down to lap over and around the upper end of the mounting ring 12 so as to protect the ball bearings therewithin. This head 13 is provided with an arm 27 extending inwardly from one side and horizontally toward the center to screw-

threadedly receive the upper end of the pin 23 axially of the head and a lock nut is provided on the upper end of the pin 23 to prevent accidental displacement of the pin from the head arm. The 5 lower end of the pin 23 screwthreadedly passes through the transverse bar of a downturned yoke 28 so as to have the bar of the yoke in close proximity to the under side of the arm 22 and a lock nut 29 is provided on the end of the pin 23 which 10 projects below the yoke bar so that the bar 28 serves as a stop to prevent the pin 23 from being withdrawn upwardly through the arm 22. Thus the head 13 is retained in place on the mounting ring 12 to permit the head to revolve around over 15 the ring 12 but preventing its being tipped over or being lifted upwardly therefrom.

On the top side of the arm 22 is mounted a pulley wheel 30 to revolve about a vertically disposed axis and a cable 31 having its upper end 20 secured to the arm 27, here shown as on the side of a web reenforcing the arm, is carried around under the arm 27, around the pulley 30 and over and down around the pulley 24 to be carried downwardly through the ring 12 and into the 25 housing 11 to have its lower end pulled downwardly by spring tension, the cable being here shown as attached to an equalizing bar 32 which is engaged with the upper ends of springs 33, here shown as two in number, the lower ends of which 30 springs are attached to a bar 34 which is in turn secured to a side of the housing 11. By means of these springs 33, the cable 31 is pulled tending to revolve the head 13 around horizontally over the mounting ring 12. A stop post 35, Fig. 6, is 35 secured to the arm 27 to extend downwardly therefrom to be in the path of the arm 22 whereby the post 35 will strike the arm 22 and prevent further rotation of the head 13 in that direction. Adjacent the place of contact of the 40 post 35 with the arm 22 is mounted a bracket 36 which has a latch member 37 pivotally secured thereto and urged upwardly by a spring 38, the tension of which is adjusted by means of a screw 39 bearing upwardly thereagainst. The under- 45 side of the post 35 is cut to have a face sloping downwardly and outwardly in relation to the under side of the arm 22 and the latch member 37 is formed to have a notch removed therefrom with a post engaging face such that when the 50 post 35 approaches the arm 22 the diagonally positioned under face of the post 35 will strike an outer sloping edge of the latch 37 tending to depress it so as to allow the post to travel thereover and have the sloping face of the notch in 55 the latch member come up behind the post 35 tending to urge the post 35 toward the arm 22 by reason of the spring 38 carrying the latch member upwardly. This sloping face in the notch is so disposed that while it will normally retain the 60 post 35 against the arm 22, the post 35 may be pushed back thereagainst with sufficient pressure to carry the latch downwardly and permit the post to escape from engagement with the latch. 65

A shaft 40 is mounted across the head 13 in a horizontal position, here shown as on a chordal line rather than on a diameter, and has its ends rockably carried through journal boxes to extend outside of the head on each side. Gate arms 41 70 and 42 are fixed to the respective projecting ends of this shaft 40 in such a manner that as the shaft may be rocked, the arms may be correspondingly rocked. These arms are here shown as channel bars having wood extensions 43 fixed thereto to 75 form the gate proper and carry counter-weights

44 at their rear ends to overbalance that portion of the gate extending forwardly of the shaft 40. The lengths of the arms back of the shaft 40 are made such that the counterbalance will strike the base 10, as indicated in dotted lines, Fig. 1, when the gate is in its extreme upper raised or opened position. 5

Referring again to the yoke 28, a cylinder 45, shown in more detail in Fig. 5, is mounted on a base 46 which is rockably engaged by cap screws 10 47 extending through the lower ends of the arms of the yoke 28 so as to rockably carry the cylinder therebetween. This cylinder is provided with a piston 48 which is without packing but is provided with a plurality of annular grooves. A piston rod 15 49 is connected with the piston 48 and extends upwardly through the cylinder head 50 through a packing gland 51 and is directly connected by a yoke 52 on its upper end with the lever 53 which is secured to the shaft 40. The yoke 52 is screw-threadedly engaged on the upper end of the rod 49 so that the piston 48 may be adjusted somewhat in respect to its distance from the end of the lever 53. The head 50 is provided with a discharge opening and a discharge hose 54 is connected to the head to be in communication with this opening. The cylinder base 46 is provided with an opening 55 from a central passage 56 which extends transversely across the casting. In one end of this casting or base 46 is a valve 57 adapted 30 to intercept the passage 56, which valve has a rod 58 connected thereto normally carried upwardly by means of the spring 59. This rod 58 extends on up in a guided relation through the head 50 and is turned over thereabove and carried around 35 the piston rod 49 to form a ring through which the rod may freely slide. A collar 60 is adjustably carried on the piston rod 49 so as to be carried against the rod 58 so as to push the rod downwardly and overcome the spring 59 to close the 40 valve 57 upon sufficient downward travel of the piston 48 in its cylinder.

Within the housing 11 is placed a comparatively shallow pan 61 to contain a relatively small amount of oil. The housing 11 is provided with 45 a floor preferably in the form of a grid with depressions therein to receive and locate the pan 61 so as to prevent it from being shifted about over the floor. Over this pan 61 is placed a tray or cover 62 which serves as a platform to carry an 50 operating pump 63 and its driving motor 64. This pump 63 has an intake pipe 65 extending down through the cover 62 well toward the bottom of the pan 61 and is further preferably provided with an automatic relief having a discharge pipe 66 returning through the cover to discharge into the pan 61. The pump 63 with its automatic relief is not shown here in detail since its structure per se does not enter into my invention and since it may be obtained 55 commercially. The pump 63 discharges through a throttling valve 67 which has a by-pass pipe 68 leading back through the cover 62 to discharge into the pan 61. After the by-pass valve 67, is provided a check valve 69 mounted in such 65 manner that flow through it may be had from the valve 67 but reverse flow from the check valve toward the by-pass valve is prevented. The line from the pump continues with a side outlet opening being provided into which is 70 fitted a hose line 70 and after the side outlet is a solenoid operated valve 71 normally open, then a cut-off valve 72 also normally open and finally a fitting 73 normally carrying the flow from the pump back down through the cover 75

62 to discharge into the pan 61. The overflow hose 54 is here shown as being connected to the fitting 73 to allow the hose to discharge through the fitting into the pan 61.

5 The hose 70 is carried upwardly to be engaged with a fitting 74 which discharges in one direction through a pipe 75 and around into that end of the passage 56 in the base 46 which may be intercepted by the valve 57. The fitting 74 discharges in another direction through a check valve 76 and thence into the other end of the passage 56. The check valve 76 is mounted between the fitting 74 and the base 46 so as to permit flow in that direction but preventing flow in the opposite direction. A connection is provided between the lower end of one of the arms of the yoke 28 and the valve 72 whereby horizontal rotation of the head 13 will operate the valve 72 such that with the gate in its normal position, the valve remains open, while in the horizontally rotated position the valve will be closed. This connection is here shown as comprising a two-part, telescoping, square sectioned tube 77 the upper end of which is pinned loosely to an extension of the arm from the yoke 28 while the lower end is pinned to the valve plug, rocking connections being provided between the tube and the plug and between the tube and the yoke arm but so formed as to have the tube revolve with the arm. By reason of this telescoping connection, it is not essential that the valve 72 be located on the axis of rotation of the head 13.

In describing the method of operating the gate, reference is made to the diagram as shown in Fig. 9, wherein it is assumed that the gate is to be employed to protect a crossing of a highway or the like with a railroad which has a track 80, the rails of which are in circuit with a block battery 81. This battery is in a permanent circuit with the winding 82 of a relay switch 83, which switch is preferably mounted within a box 84 carried by standards on the cover 62 of the pan 61 within the housing 11. This relay switch 83 is normally open and is employed to close the circuit of a power line when the axle or wheels of a car or train operating upon the track 80 completes the circuit through the battery 81. When the relay switch coil 82 is thus energized 50 the switch 83, here indicated as a double-pole switch is closed and a circuit is provided therefrom to include the motor 64, the winding of the solenoid valve 71, a warning bell 86, here shown as being mounted on the head 14, Fig. 1, and a plurality of warning lights 85 here shown, Fig. 10, as being arranged behind glasses or lenses to display the word "Stop". The winding of the solenoid valve 71 thus being energized, the valve is closed and the pump 63 then being operated 55 by the motor 64 forces oil up through the hose 70 to within the cylinder 45, the valve 57 being closed so that the oil may flow through the opening 55 from that end of the passageway 56 to which is connected the check valve 76. It is to be understood of course that the gate is normally returned to its upper or open position by means of the counter-weight 44 so that the piston 48 is initially at the lower end of the cylinder 45. As the pump continues to discharge oil, the piston 60 48 will be raised in the cylinder 45 so as to force the rod 49 upwardly and thereby rock the shaft 40 around to lower the gate. The piston 48 continues traveling upwardly under the pressure exerted by the incoming oil until a switch is operated to stop the motor.

The switch is preferably in the form of a mercury tube switch which may be rocked to close and open the motor circuit without having any exposed arc or spark. Referring to Figs. 3, 4 and 7, the mercury tube 87 is here shown as being carried within a housing 88 which is rockably mounted on the side of a bracket 89. The housing 88 is pivoted about a pin 90 which is so located in respect to the housing that the housing will normally tend to drop downwardly by 10 its outer end so as to rock the tube 87 therewith to a "closed" position. This downward rocking of the housing is limited by the rear end of the housing striking a lip 91 turned outwardly from the bracket. A second pin 92 is carried by the housing to be above and to the rear of the pivot pin 90 and an arm 93 is carried by the shaft 40 to be swung around against the pin 92 so as to have rocked the housing 88 around to tilt the tube 87 to the "open" position by the time 20 the shaft 40 has carried the gate down to its horizontally disposed position. The upward rocking of the housing 88 is limited by the upper corner of it striking the lip 91 as indicated in Fig. 7. The bracket 89 is here shown as being mounted over the edge of an oil well through which the shaft 40 extends, to have the housing 88 immediately above the shaft 40. The arm 93 is pivotally attached to a clamp 94 which is adjustably attached to the shaft 40 in the same 30 manner as a C clamp. The arm 93 is attached to the bracket 94 by means of a pin 95 rockably supporting the arm and the arm is shaped at its lower end below the pivot pin 95 to have one corner rounded off to permit the arm 35 being turned about the pin 95 away from the housing pin 92 but having the opposite corner left intact to form a foot which will strike the clamp 94 so as to prevent rotation of the arm 93 in the opposite direction. A spring 96 between 40 the arm 93 and the clamp 94 is employed to rock the arm 93 around to its limit of travel as determined by the contact of this corner with the clamp. This mounting of the arm 93 is employed as a means for preventing breakage or 45 damage of any sort and to permit approximate rather than exact adjustments of the bracket 89 and the clamp 94 in respect to each other so that after the housing 88 has been rocked to its upper position the shaft 40 may continue revolving 50 slightly since the arm 93 may be rocked backwardly to overcome the pull of the spring 96 in the event of this over travel.

Thus the gate is in the lowered position; a pressure is in the cylinder 45 under the piston 55 48 tending to hold the gate in that position; the motor has been disconnected from the energizing circuit; the solenoid valve 71 remains closed by reason of its coil still remaining in that circuit; and the lights 85 and the bell 84 remain 60 energized to give the visible and audible warnings. Now should sufficient oil leak past the piston 48 to above the piston, the leakage, if sufficient, may overflow and return back through the hose 54 to the pan 61. Also if this leakage 65 is sufficiently great, pressure under the piston 48 becomes reduced so that the weights 44 may tend to lift or swing the gate, but immediately the upward swing starts the arm 93 is carried 70 away from the pin 92 to permit the housing 88 to drop and thereby again close that part of the energizing circuit which includes the motor 64 so that the pump 63 is again set in operation to replenish the oil below the piston 48 and return it to its upper position.

The upward travel of the piston rod 49 is limited by means of an adjustable screw 97 which extends down through the head cap 14 to be struck by the lever 53, Fig. 1. In order to prevent 5 too great an impact against this screw, I employ the customary rods 88 hingedly connected to the outer ends of the gates which drop down and strike the roadway or ground to arrest further downward travel of the gates, Fig. 10. The length of the rod 88 and the adjustment of the screw 97 are correlated so that both operate 10 to limit the downward swing of the gates.

The gate thus remains in the horizontal position 15 guarding the crossing until the track or block circuit is opened, whereupon the relay switch 83 is opened; the bell 84 and lamps 85 deenergized; the motor 64 stopped; and the coil in the solenoid valve 71 deenergized to permit the valve to open and thus allow oil to drain back 20 from the cylinder 45 to the then open valve 51 and down through the hose 70, through the open solenoid valve, the open valve 72, and the fitting 73 into the pan 61. This draining of the cylinder 45 is further accentuated by reason of 25 the weights 44 tending to lift the gate and force the piston 48 down through the cylinder to expel the oil. This action normally takes place when the gate is allowed to remain in its position to swing across the highway being guarded but 30 should the gate have been struck or rocked around while in the horizontal position, even though the relay switch 83 has been opened, the oil cannot escape from the cylinder 45 since the valve 72 has been closed by the horizontal rotation 35 of the gate and the return flow of the oil is cut off thereby. However as soon as the pressure against the gate having caused the horizontal rotation is removed, the springs 33 will pull the head 13 around to bring the gate back to its 40 normal position which position then has caused the valve 72 to be opened so as to allow the drainage of the oil and permit the weights 44 to carry the gate to its open position.

Just before the weights 44 strike the base 10, 45 the collar 60 having been properly adjusted along the rod 49 will strike the overturned end of the rod 58 so as to close the valve 57 and shut-off further drainage of the oil from the cylinder 45 and thereby provide a cushion of oil under the 50 piston 48 to check the speed of the falling weights 44 so as to allow them to come into contact with the base 10 with a much lessened impact.

The cable 31 may be hooked-up with the head 55 13 so as to selectively form right and left hand gates. The hook-up is here shown as for a left

hand gate and to change it over to a right hand gate, the stop post 35 is mounted on the other side of the arm 27 so as to be in the path of the arm 22 on that side and the latch bracket 36 is correspondingly shifted to the other edge of the arm 22, and the pulley 30 shifted to the other side of the pulley 24. The cable 31 is then brought up around the opposite side of the pulley 24, carried around the shifted pulley 30 and then attached to the arm 27.

The pump 63 has a much greater capacity than required to fill the cylinder 45 within the time desired, and the throttle valve 67 is employed to control the rate of delivery of the oil to the cylinder. By adjusting the valve to alter the bleed therefrom through the line 68, the required rate may be obtained. The pump, being provided 15 with a built in relief valve discharging through the return 66, can not deliver pressure exceeding a predetermined amount, and hence if for any 20 reason the motor remains energized no damage may be done to the system.

While I have here shown my invention in the one specific form as now best known to me, it is 25 obvious that structural changes may be made without departing from the spirit of the invention and I therefore do not desire to be limited to that precise form beyond the limitations as may be imposed by the following claims.

I claim:

1. In a crossing gate, a standard, a gate supported by the standard to have an arm rockable both vertically and horizontally, latch means for holding the arm in a normal rigid position as to horizontal movement against normal pressures but releasing the arm upon an impact on the gate.

2. In a crossing gate, a gate arm, arm supporting members comprising a standard and a head revolubly mounted on the standard, and a latch mechanism interposed between the said members normally holding the members rigidly one in respect to the other, said mechanism being formed to completely release the holding effect of the mechanism of one member in respect 45 to the other following a slight initial relative travel thereof.

3. In a crossing gate, a gate arm swingable both vertically and horizontally, means for swinging the gate arm vertically, cut-off means for rendering said swinging means inoperative, and means connecting with and operating the cut-off means upon horizontal swinging of the gate arm.

JOSEPH H. STALEY. 55
